Application April 29, 1947, Serial No. 744,670
 In France July 24, 1945

Section 1, Public Law 690, August 8, 1946
 Patent expires July 24, 1965

4 Claims. (Cl. 172—126)

1

This invention relates to improvements in driving mechanisms of the well-known electro-magnetic pawl and ratchet type with self-interrupter contacts for step-by-step rotary switches of the kind used in automatic telephone systems.

In rotary switches of a commonly-used type, particularly in automatic switching telephone equipment, rotation is caused by the action of a pawl, attached to the armature of an electromagnet, said pawl acting on a ratchet wheel keyed to the wiper block shaft. For the purpose of obtaining oscillatory motion of the armature, and thus of the pawl, a contact is inserted in the energizing circuit of the electromagnet and operated by said armature in such a manner as to open said energizing circuit when required and cause, through a spring, the return of the armature to its initial or rest position. During a complete back and forth excursion of the armature, the pawl causes the ratchet wheel to rotate one tooth and the wipers to move ahead one step.

In the equipment commonly in use, the opening and closing of the contact inserted in the energizing circuit of the electromagnet takes place at one and the same position of the armature. Therefore, in practice, operation is possible only thanks to the mechanical inertia of the moving parts and the self-inductance of the electromagnet winding, which requires delicate adjustments which hold good only within narrow voltage limits.

Various solutions have been offered to improve reliability of operation, particularly through methods making it possible to have the opening and closing of the electromagnet energizing circuit take place at different positions of the armature, in order to allow a sufficient stroke of said armature, for the purpose of improving reliability of the moving of the pawl from one tooth to the next. However, while the solutions offered permit improved operation, said operation still remains very sensitive to the variations of the energizing voltage.

The object of this invention is to provide a driving mechanism for the wipers of rotary switches in which the opening and closing of the contact inserted in the energizing circuit of the electromagnet are made dependent, on the one hand, on the position of the armature at the end of its attraction stroke and, on the other hand, on the position of said armature at the end of its release stroke. Thus, said mechanism, by means of simple adjustments, makes it possible to have perfectly satisfactory and reliable operation, this holding true for all energizing voltages capable of attracting the armature of the electromagnet, said

2

operation no longer depending only on the inertia of the moving part and self-inductance of the winding.

A characteristic of the invention is to be found in the fact that it makes use, for actuating the contact inserted in the energizing circuit of the electromagnet, of an auxiliary arm associated with said electromagnet, and operated by the driving mechanism of the rotary switch at the end of the attraction and release strokes respectively, being maintained attracted or locked throughout the attraction stroke and released throughout the release stroke.

The principles on which the invention rests and various other characteristics will be made clear by the description which follows, which will be given in relation with the appended drawing in which:

Figure 1 is a side elevation of the driving mechanism for a rotary switch of the "ten position" type.

20 To make the figure clearer, the wipers and bank contacts have not been shown.

Figure 2 is a top view of the mechanism illustrated at Figure 1.

Figure 3 is a front elevation of the mechanism 25 shown on Figure 1.

Figure 4 is a detailed view showing the arrangement for operation of the auxiliary arm by the driving mechanism of the switch.

30 A bell crank-shaped yoke or pole piece 28 is attached to platen 1 by screws 35 and 36. Said bell crank 28 carries electromagnet 27, attached to it by a screw 29. Bell crank 28 also carries, attached by screws 31 and 32, and parts such as 31, a shaft 11, about which armature 10 of the switch-driving mechanism can pivot. Part 28 completes the magnetic circuit for the assembly constituted by electromagnet 27 and armature 10.

35 The armature 10 is attached, by screw 38, to one of the extremities of a leaf spring 9, the other end 40 of which is maintained in a block 39, riveted to pawl 8. Pawl 8, in turn, meshes with a ratchet wheel 4, keyed to sleeve 3, which can rotate freely about shaft 2, attached by nut 33 to frame 1. The moving brush block, not shown, is mounted on 45 sleeve 3. Stop pawl 5 is attached to lug 49, made by folding over frame 1; stop 6, for driving pawl 8, also is attached to said lug.

40 Lugs 14 and 34, obtained by folding over frame 1, have holes through which rod 12 can slide. 50 The lower part of said rod, 12, carries a threaded sleeve 13, part 15 of which constitutes a nut. Sleeve 13 can slide in the hole provided in lug 14 and carries the upper end 41 of pawl 8. The hole provided in end 41 has a larger diameter than sleeve 13, in order to enable pawl 8 to oscillate

about the axis of 12. The upper part of rod 12 carries a spring 18 which seats, at its upper part, against lug 34, and at its lower end against nut 17. The adjustment of the tension of said spring can be effected by moving nut 17 which is then maintained in the position chosen by lock nut 16.

On the upper part of rod 12 (Figure 4) is screwed a sleeve 42 with a shoulder 43, this sleeve passing by way of auxiliary arm 22 through an opening 44 (Figure 2) and carrying a thread onto which are screwed nut 23 and lock nut 24.

Auxiliary armature 22 is connected to yoke 28 by a screw 25, arranged to permit vertical pivotal movement of arm 22, and by a spring 26. A central perforation is provided in said auxiliary arm for the head of screw 29.

At rest, the various parts occupy the positions shown on the drawing. Spring 18 presses down on rod 12 and said rod, by the action of nut 23, maintains auxiliary armature 22 in contact with yoke 28. In that position, insulating plunger 21, fixed to the end of auxiliary armature 22, forces moving contact 20 against fixed contact 19. The circuit of electromagnet 27, passing through said contacts, is thus closed.

When the driving circuit for the rotary switch is completed, armature 10 is attracted. It raises rod 12, compressing spring 18. Auxiliary armature 22 no longer is subjected to the action of said spring 18 but remains stuck to pole piece 28, through the action of the lines of force of electromagnet 21. When pawl 8 has fallen into the following tooth of wheel 4, shoulder 43 (Figure 4) comes against auxiliary armature 22 and causes its release, which frees the spring of moving contact 20, which rises, opening contact 19-20. The circuit of electromagnet 27 opens and armature 10 ceases to be attracted, whereupon the action of spring 18 has the effect of moving rod 12 toward its lower position. Said rod actuates pawl 8, which causes the rotation of wheel 4 (which moves ahead one tooth). At the end of the release stroke, nut 23 (Figure 4) carries with it armature 22 and brings it back to rest position against piece 28, contact 19-20 is closed and the same cycle of operations starts all over again throughout the duration of closing of the driving circuit of the rotary switch.

It will be noted that the adjustment of nut 23 along rod 12 (Figure 4) is so arranged that the motion of armature 22 takes place near the end of the return of the system to the rest position. Similarly, shoulder 43 comes against this armature only near the end of the attraction stroke of armature 10. It will be seen that, in such conditions, contact 19-20 will be open only when pawl 8 will have moved on from one tooth to the next. Said contact 19-20 will be closed only when, under the action of spring 18, pawl 8 will have caused wheel 4 to move ahead one tooth. This guarantees complete reliability of operation.

It would be possible, in order to increase the flux acting on auxiliary armature 22, to provide a certain number of holes in the horizontal part of piece 28.

It remains obvious that it would be possible to modify the shape and arrangement of the various parts, all embodiments making use of an auxiliary armature maintained locked by the flux of the electromagnet and acting on the contact inserted in the circuit of said electromagnet remaining within the scope of said invention.

I claim:

1. Driving mechanism for rotary switches of the electromagnetic pawl and ratchet type comprising in combination a frame member, a yoke piece mounted on said frame member, an electromagnet mounted on said yoke piece, an armature pivoted to said yoke piece, a driving pawl operatively connected to said armature and engaging the teeth of a ratchet wheel rotatably mounted on said frame member, an auxiliary armature resiliently supported on said yoke piece, contacts for closing and opening the circuit of said electromagnet, means on said auxiliary armature for cooperating with said contacts, a link member mounted in guides on said frame and carrying at one end a stop member engaging said driving pawl and at the other end a stop member engaging said auxiliary armature and a spring on said link member.

2. Driving mechanism for rotary switches of the electromagnetic pawl and ratchet type according to claim 1, wherein one of said contacts is spring mounted to be normally out of contact with the adjacent fixed contact and the auxiliary armature carries a stop to engage said spring mounted contact.

3. Driving mechanism for rotary switches of the electromagnetic pawl and ratchet type according to claim 1, wherein said link member comprises a threaded rod and the stop members comprise sleeve members adjustably mounted on said rod.

4. Driving mechanism for rotary switches of the electromagnetic pawl and ratchet type according to claim 1, wherein said spring is positioned between one of said guides and an adjustable stop on said link member arranged for adjusting the tension on said spring.

YVES J. G. JUILLARD.
